UNITED STATES PATENT OFFICE.

J S. MITCHELL, OF STUTTGART, ARKANSAS.

SHOE SOLE.

Application filed January 28, 1925. Serial No. 5,272.

To all whom it may concern:

Be it known that I, J S. MITCHELL, a citizen of the United States, residing at Stuttgart, in the county of Arkansas and State of Arkansas, have invented certain new and useful Improvements in a Shoe Sole, of which the following is a specification.

This invention relates to improvements in shoe soles and has for its principal object to provide a simple and efficient means for increasing the thickness of the portion of the sole which is disposed adjacent the outer edge of a shoe. As is a well known fact, shoes are worn out quickly at the outer edges of the soles than at the inner edges and consequently a shoe will lose its shape.

One of the important objects of the present invention is to provide a shoe sole which is of such construction as to increase the durability of the sole and reinforce the portion of the sole which is subject to the most wear.

A further object is to provide a shoe sole of the above mentioned character, which is simple in construction, inexpensive, strong and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a bottom plan view of the shoe sole embodying my invention.

Figure 2 is an edge elevation thereof, and

Figure 3 is a sectional view taken approximately on line 3—3 of Figure 1.

In the drawing, wherein for the purpose of illustration is shown the preferred embodiment of my invention, the numeral 1 designates a shoe sole which is formed of a single piece of leather. The outer edge 2 of the shoe sole is slit for its entire length as illustrated in dotted lines in Figure 1 of the drawing. The slit 3 extends inwardly to the longitudinal center of the sole as also illustrated in Figure 1 as well as in Figure 3.

Adapted to be inserted between the divided portions 4 and 5 formed by the slit 3 in the outer edge of the sole 1 is a wedge shaped piece of leather 6. The usual shoemaker's cement is used for securing the wedge 6 in the slit 3 formed in the outer edge

of the sole 1 and after the wedge has been inserted and cemented in the slit between the divided portions 4 and 5, the outer edge of the wedge is trimmed to conform with the outer edge of the sole.

As further illustrated in Figure 2 of the drawing, the portion of the wedge which is disposed adjacent the toe portion of the sole is tapered gradually as illustrated at 7.

The provision of a shoe sole of the above mentioned character, will cause the portion of the sole which is adapted to be disposed adjacent the outer edge of the shoe to be of greater thickness than the remaining portion of the sole as clearly illustrated in Figure 3. As stated above, the outer edge of the sole is subject to most wear and by providing the insert in the slit formed in the outer edge of the sole, the durability of the sole is increased and thereby will prevent the shoe from losing its shape.

The provision of a sole of this character furthermore will save a shoemaker considerable time and labor in repairing shoes as heretofore necessary to insert a number of patches between the welt and the sole or else tack on a patch on the bottom of the sole at the outer edge thereof. Furthermore the provision of a sole of the above mentioned character will not affect the appearance of the shoe.

While I have shown the preferred embodiment of my invention, it is to be understood that various changes in the size, shape and arrangement of parts may be resorted to without departing from the spirit of the invention and the scope of the appended claim.

Having thus described the invention, what I claim as new and desire to secure by Letters Patent is:

An outer sole for shoes, the outer edge thereof being slit longitudinally for its entire length, said slit extending inwardly to the longitudinal center of the sole, a leather wedge inserted in said slit between the divided portions formed thereby and cemented therein whereby the portion of the sole disposed adjacent the outer edge of a shoe is of greater thickness than the remaining portion of the sole, the portion of said wedge adjacent the toe portion of the sole tapering gradually toward the end of the wedge.

In testimony whereof I affix my signature.

J S. MITCHELL.
